UNITED STATES PATENT OFFICE

JAMES R. HAIGHT, OF ADRIAN, MICHIGAN.

FOUNTAIN-PEN.

SPECIFICATION forming part of Letters Patent No. 299,219, dated May 27, 1884.

Application filed October 1, 1883. (No model.)

To all whom it may concern:

Be it known that I, JAMES R. HAIGHT, of Adrian, in the county of Lenawee and State of Michigan, have invented new and useful Improvements in Fountain-Pens; and I do hereby declare that the following is a full, clear, and exact description thereof, reference being had to the accompanying drawings, which form a part of this specification.

10 This invention relates to certain new and useful improvements in the construction and operation of that class of pens known as "fountain-pens."

15 The invention consists in the peculiar construction of the various parts and their combinations, by means of which a more perfect and regular feed is obtained than is had in the pens of a similar class now in use, and wherein the danger of accidental overflow of 20 the ink is reduced to the minimum, as more fully hereinafter described.

25 Figure 1 is a central longitudinal section of my improved pen. Fig. 2 is a sectional elevation. Fig. 3 is a cross-section on the line $x-x$ in Fig. 1.

In the accompanying drawings, which form a part of this specification, A represents a cylinder-fountain, one end of which is rigidly closed, as at a , while into the opposite end is 30 screwed a hollow plug, B, one end of which projects beyond the end of the fountain, as shown in Fig. 1, the bore of the projecting end being larger than the bore of the inclosed end.

35 E is another plug or pin, the diameter of which is the same as the smaller bore of the plug B, into which the plug E slips, or is screwed, if preferred, the space left between this plug and the wall of the larger bore of the 40 plug B forming a space in which to insert the pen, which may be of any of the known constructions. This plug E is split or slotted, as shown at b , for a part of its length, and a small hole or orifice, c , connects said slot with 45 the fountain-chamber.

D is a cap, which is slipped into the space between the two plugs on the opposite side from the pen C, and is made of the form substantially as shown in the drawings, to inclose 50 the space between it and the pen, thereby forming a chamber into which the slot in the plug E opens, such chamber being for the pur-

pose of holding a sponge or other suitable absorbent. A slot, d , is cut in each side of this cap coincident with the lower end of the slot 55 in the plug E, to admit air at that point between the absorbent and the fountain.

F is a detachable cap, designed, when the pen is in use, to engage with the projecting end of the plug B to protect the pen, and when 60 the latter is in use to engage with the opposite end of the fountain-cylinder, as shown, to form an extension of the pen-holder.

It will be noticed in this construction that when the pen is in use there is free access of 65 air to the ink in the slot in the plug E, by means of which the column of ink is retarded in its flow or held in abeyance by atmospheric pressure, the orifice in the plug E, connecting with the fountain, allowing the air to pass and 70 the ink to flow out in the sponge, which latter feeds ink to the pen as fast as required, such sponge being saturated from the fountain for that purpose through the means described. When the pen is held upright in position after writing, the ink above the sponge makes 75 a supercharge, causing some to pass out into the pen, where the capillary attraction of the concave of such pen holds the ink ready for 80 use.

It will also be noticed that the fountain is 85 detachable from the sponge-holder, and that the latter may be made adjustable to different lengths of pens, which, when in place, are securely held by the spring of the plug E, obtained by its being split, as described.

I am aware of Patent No. 260,134, and make no claim to the construction shown therein.

What I claim as my invention is—

1. The combination of the cylinder-reservoir closed at the top, the porous material or sponge in the chamber formed by the pen, and a shoe or cap, a central plug with an orifice and slot affording communication between said reservoir and such porous material, said slot also opening to the air through coincident openings in the cap or shoe, substantially as and for the purposes set forth. 90

2. The cylindrical ink-reservoir, open at its lower end only, in combination with a detachable holder inclosing a central plug, slotted and bored to afford communication between such fountain and the pen, the shoe or cap and pen, by means of which a chamber is 100

formed to receive the porous material, the parts being constructed and operating substantially as described and shown.

3. In a fountain pen, the reservoir, pen, 5 shoe, or cap, such pen and shoe inclosing the porous material, with a central plug slotted and bored as described, and adapted to fur-

nish the requisite atmospheric pressure at a point between such porous material and the fountain, substantially as set forth.

JAMES R. HAIGHT.
